UNITED STATES PATENT OFFICE.

FRANK JOHNSON AND BURTON M. APPLEBEE, OF BROOKLYN, NEW YORK.

FOLDING GAME-TABLE.

1,266,125.

Specification of Letters Patent.

Patented May 14, 1918.

Application filed May 5, 1917. Serial No. 166,705.

To all whom it may concern:

Be it known that we, FRANK JOHNSON and BURTON M. APPLEBEE, citizens of the United States, residing in the city of New York, borough of Brooklyn, in the county of Kings and State of New York, have invented a certain new and useful Improvement in Folding Game-Tables, of which the following is a specification.

10 The invention relates more particularly to tables on which pool, billiards and analogous games are played, and the main object of the invention is to provide a table of this type which may be folded into small compact 15 pass for storage or transportation and easily unfolded and extended for service.

A further object is to provide a foldable bed for such tables which shall be rigid and plane when extended, and means for locking such bed to a foldable cushion-frame in such manner as to "break joints" and maintain the rigidity.

Another important object is to provide means for preventing the formation of creases in the bed-covering while in the folded condition, and to provide a simple and efficient rail-cushion.

Another object is to provide a structure in which the folded bed may be received 30 and held within the folded rails or frame as a receptacle for storage or transportation.

The invention consists in certain novel features of construction and arrangement by 35 which the above and other objects are attained, to be hereinafter described and claimed.

The accompanying drawings form a part 40 of this specification and show the invention as carried out in a pool table.

Figure 1 is a plan view of the table in the open or distended condition.

Fig. 2 is a corresponding side elevation.

Fig. 3 is a vertical longitudinal section 45 taken on the line 3—3 in Fig. 1, and partly in elevation.

Fig. 4 is a plan view of the under face of the table.

Fig. 5 is a vertical section through certain 50 portions of the rail and bed, taken on the line 5—5 in Fig. 1.

Fig. 6 is a transverse section on the line 6—6 in the preceding figure.

Fig. 7 is a side elevation showing the 55 frame and bed in the folded and packed condition.

Fig. 8 is a corresponding edge view.

Fig. 9 is a section taken on the line 9—9 in Fig. 7 and partly in elevation.

The remaining figures are on a larger 60 scale and show details.

Fig. 10 is a vertical section through the rail, bed, and cushion.

Fig. 11 is a plan view of one of the 65 pockets seen from below.

Fig. 12 is a vertical section showing the construction of one of the adjustable supporting legs.

Fig. 13 is a vertical section on a still larger scale showing the construction of the 70 bed and its covering.

Fig. 14 is a plan view of the bed without its covering and with certain parts removed from certain portions, and partly in horizontal section to show the direction of 75 the grain of the wood.

Similar letters of reference indicate the same parts in all the figures.

The table is rectangular and shown as having a length about twice its width, and 80 comprises two main portions, the rails and the bed. The rails consist of an outer frame A securely joined at the corners and preferably reinforced by L-shaped plates A¹ set in the upper face at those points, and the 85 cushions B fastened to the inner faces of the frame and of less depth than the latter to provide a rabbet in which the bed is received and held. This frame is divided transversely at the center line of each long 90 side and hinged on the under face as at A² to fold upon itself with the cushions presented outwardly, and the hinges are sufficiently offset from the plane, as shown in Figs. 2 and 3 to provide a space between 95 the adjacent faces when folded, which with the rabbets affords an open-sided pocket or receptacle to contain the bed, as will be described.

The bed is in three parts joined together; 100 the main central portion C is approximately square and the leaves C¹ C² are each of approximately half its area and are connected to such main portion by hinges C², so that the smooth upper faces of the leaves C¹ C² fold upon the smooth upper face of the central portion C. The hinges are located on the upper surface at the margins of the bed to lie concealed beneath the cushions B at each side which are hollowed out or recessed to receive them, see Figs. 5 and 6. 105

On the under face of the bed along the

5 margins are turn-buttons D arranged to engage in housings or keepers E on the under faces of the frame A and hold these parts stiffly distended with the buttons lying across the joints. The under faces of the 10 leaves C¹ C¹ and central portion C carry short blocks or lugs F arranged to extend across the bed-joints and maintain the bed in a plane condition.

10 15 The cushions B are interrupted at the corners and at the midlength of the sides to match to the openings c c in the bed which form the mouths of the pockets G. The latter are not permanently attached to the bed but are of net secured to open rings G¹ each 20 adapted to be compressed to enter a series of housings G² located around the opening on the under face of the bed and to expand and engage therewith.

20 25 The table is designed to rest upon any suitable surface, as a dining table, and is supported by four short legs H hinged at H¹ to the under faces of the leaves C¹ C¹ and adapted to project downwardly at a right angle therefrom for service or to be folded thereon.

30 The rails are held against lateral movement at the midlength joints by a vertical ridge or dowel A⁴ on one member received in a corresponding groove a in the other, as shown in Figs. 1 and 7, and thus the frame is stiffened at these joints.

35 It will be noted that the joints in the rails are located on the center line of the main portion C of the bed, while the folding lines of the latter are located midway between the rail-joints and end rails, thus "breaking joints" and insuring the required rigidity.

40 Short turn-buttons J J on the rails extend across the line of junction to the under face of the bed at certain points and aid the buttons D in holding the bed firmly and stiffly in the rabbet of the rails.

45 Assuming the table to be in condition for service, as in Figs. 1, 2, 3 and 4, and is to be folded; the table is partly elevated by turning on one edge or pair of legs, the pockets G are removed by compressing the 50 rings G¹ sufficiently to release them from their housings G², the legs are then folded down upon the bed, and the series of buttons D and J are turned to free the bed from the rabbet in the rails and is removed therefrom, and its leaves C¹ C¹ folded upon the main portion C. The frame is then folded upon itself, the offset condition of the hinges A³ being sufficient to permit the members to lie parallel when thus folded with the 55 positively located housings E and E of the two portions in contact, see Fig. 8, and forming an open topped pocket or receptacle into which the folded bed is slid and closely received, see Figs. 7, 8 and 9. The open mouth 60 of such receptacle is then closed by a hollow

cap M having a length and thickness equal to the width and thickness of the folded frame, and is fastened to the latter by hooks K K engaged in eyes K¹ K¹ suitably located on the outer faces of the frame and on the 70 ends of the cap, and to prevent spreading of the lower edges of the folded frame, such edges are held in proper relation by similar hooks L and L and eyes L¹ and L¹ on the end-rails.

75 The cap M is shaped to match to the ends of the cushions B at the notches provided for the side-pockets c, and has a ridge M¹ at one end and a groove m at the other matching to the corresponding groove a and ridge A⁴ on the rails. The ends of the cap are also notched as at m¹ in Fig. 8 to receive one set of hinges C² of the bed, and the cap is provided with a suitable handle M² on its upper face by which the whole may be conveniently 85 carried.

A reversal of the operation unfolds the table and conditions it for service as a pool table.

90 The bed is preferably of wood to provide the desired strength combined with lightness, and it is essential that its upper face be plane and any tendency to warp be resisted, to this end the bed is a built-up structure comprising a series of separated strips 95 C⁴, in which the grain of the wood lies in the direction of the length of the table, see Fig. 14, between two thin boards C⁵ C⁵ to which they are firmly glued and in which the grain runs in the same direction as in 100 the strips, this insures against warping longitudinally, in the direction of the grain; and to prevent curling transversely the bars C⁶ with their grain running lengthwise, but transversely of the bed, are inserted between 105 each pair of strips C⁴, fitted closely in the spaces thus provided. The bars C⁶ are of the same thickness as the strips C⁴ and are not fastened either to the surface boards C⁵ or to the adjacent faces of the strips but are 110 free so that the strips and boards may together expand or contract laterally and move relatively to the bars C⁶. To insure this freedom of movement the bars are each wrapped in an envelop of paper C⁷ before 115 the glued boards C⁵ C⁵ are applied so that while the paper may and will adhere to the boards, the bars are free to slide within the paper envelop or covering, or if the glue unintentionally reaches the bars so that the 120 paper adheres to both the bar and one or both of the boards or the strips, the movement of the joined boards and strips relatively to the bars will separate the paper in laminae and thus free the bars. The latter 125 are stiff enough to resist any tendency of the boards and strips to curl or warp laterally.

The cushions B are in sections secured to the rails and overhang on their inner edges as usual; to provide the desired resiliency 130

a cylindrical strip B¹ of rubber is cemented in a corresponding semicircular groove along such edge and projects sufficiently to receive the impact of the ball in playing.

5 Both the cushion and rubber strip are enclosed in billiard cloth B² or other fabric.

The upper face of the bed is also cloth covered as indicated in Fig. 13, and the cloth C⁸ instead of being cemented directly 10 to the upper board C⁵, is cemented to a sheet of paper C⁹ which is first cemented to such board and the cloth C⁸ then applied to the paper. By this construction, and by offsetting the hinges C² above the bed-surface, the cloth C⁸ forms a curve or roll of 15 relatively long radius when the leaves C¹ are folded and the formation of sharp creases in the cloth is avoided. The paper C⁹ may break at the fold in an irregular 20 line or may split or separate in laminæ, as above described, part adhering to the board and part to the cloth in the vicinity of the folding line.

In order that the distended table may be 25 leveled the lower portion H² of each leg is arranged to slide telescopically within the other, and a fixed bolt H³ mounted in the upper portion receives a circular thumb-nut H⁴ lying in a slot h of the portion H² which 30 is easily operated by the fingers through the notches h¹ in the upper portion to adjust the length of the leg.

The legs are hinged to the under face of 35 the bed at H¹ and each carries an arm H⁵ adapted to ride upon a spring H⁶ mounted in a recess c¹ in the bed and movably hold the leg either in the folded position parallel with the bed-surface or projecting at a right angle therefrom.

40 The invention provides at low cost a table of the pool or billiard type of sufficiently high grade for general or home use, and its folding features permit its installation in apartments in which the usual table could not be 45 accommodated for lack of space, and permits its easy transportation. Its appearance is attractive and it may be made in close imitation of the usual large table and it may be ornamented as desired or produced in various grades of size and quality 50 at corresponding prices; in the cheaper qualities beds of less costly construction may be substituted for the built-up board described, and the material used for covering 55 the bed and cushions may be correspondingly varied.

We claim:—

1. In a table of the character set forth, a bed arranged to fold upon itself and to be 60 unfolded in a plane, and a frame arranged to fold upon itself and to be unfolded and inclose said bed, the line of fold of said bed lying out of coincidence with the line of fold of said frame.

65 2. In a table of the character set forth, a

bed arranged to fold upon itself and to be unfolded in a plane, a frame arranged to fold upon itself and to be unfolded and inclose said bed, the line of fold of said bed lying out of coincidence with the line of fold of said frame, and means carried by said bed and frame for separably joining said bed and frame. 70

3. In a table of the character set forth, a bed arranged to fold upon itself and to be unfolded in a plane, and a frame arranged to fold upon itself and to be unfolded and inclose said bed in such plane condition, and to be folded and inclose said bed when the latter is in the folded condition. 75

4. In a table of the character set forth, a bed consisting of a central portion and a leaf on each side thereof arranged to fold upon said central portion, a frame adapted to inclose said bed in the unfolded condition, said frame consisting of two substantially equal portions arranged to fold upon each other. 80

5. In a table of the character set forth, a bed arranged to fold upon itself consisting of a central portion and two leaves hinged thereto one on each side thereof; a frame in two substantially equal portions hinged together and arranged to receive and inclose said bed when the latter and said frame are in the unfolded condition, the hinges of said bed and frame arranged to fold oppositely relatively to each other, and means for separably engaging said bed with said frame. 90

6. In a table of the character set forth, a bed, a frame in two portions hinged together and adapted to receive and inclose said bed, hinges at the joints of said frame, each portion having a member arranged to extend across such joint and engage the other portion to resist lateral strains on such joints. 105

7. In a table of the character set forth, a bed arranged to fold upon itself consisting of a central portion and two leaves hinged thereto, one on each side thereof, a frame in two substantially equal portions hinged together and arranged to receive and inclose said bed when the latter and said frame are in the unfolded condition, the hinges of said bed lying on the upper face and received in recesses in said frame, and the hinges of said frame on the lower face thereof, movable means for separably engaging said bed with said frame, and means on the under face of said bed arranged to overlap the joints therein and stiffen said bed. 110

8. In a table of the character set forth, a foldable bed, a foldable frame arranged to inclose said bed, movable means on said frame and bed for separably engaging said bed to said frame, and legs hinged to said bed and arranged to fold thereon. 125

130

- 4
9. In a table of the character set forth, a foldable bed, a foldable frame arranged to inclose said bed, movable means on said frame and bed for separably engaging said bed to said frame, legs hinged to said bed and arranged to fold thereon, and means for adjusting the length of said legs.
10. In a table of the character set forth, a foldable bed, a foldable frame arranged to inclose said bed, movable means on said frame and bed for separably engaging said bed to said frame, legs hinged to said bed and arranged to fold thereon, and frictional means for maintaining said legs in either 15 the folded or unfolded condition.
11. In a table of the character set forth, a foldable bed, a foldable frame arranged to inclose said bed in the unfolded condition, movable buttons on the under face of said bed, housings on the under face of said frame receiving said buttons, and lugs on the parts 20 of said bed, arranged to extend across the joints of the latter in both directions.
12. In a table of the character set forth, a foldable bed having pocket-openings therein, a foldable frame arranged to inclose said bed in the unfolded condition, means for separably engaging said bed to said frame, the latter arranged when folded to 25 form a receptacle for the folded bed, removable pockets carried by said bed, and means for separably engaging said pockets with said bed below such openings.
13. In a table of the character set forth, a foldable bed having pocket-openings therein, a foldable frame arranged to inclose said bed in the unfolded condition, means 30
- for separably engaging said bed to said frame, the latter arranged when folded to form a receptacle for the folded bed, hooks 40 surrounding such openings, compressible open rings adapted to engage such hooks by expanding therein, and pockets carried by said rings.
14. In a table of the character set forth, a foldable bed, a foldable frame arranged to inclose said bed in the unfolded condition, hinges joining the portions of said bed and offset therefrom, a layer of paper cemented to the upper face of said bed, and a 45 covering of fabric cemented to said layer, the latter and said hinges serving to prevent the formation of creases in said covering at the joints of said bed when in the folded condition.
15. In a table of the character set forth, a foldable bed, a foldable frame arranged to inclose said bed in the unfolded condition, means for separably engaging said bed to said frame, the latter arranged when folded to 50 form a receptacle for the folded bed.
16. In a table of the character set forth, a foldable bed, a foldable frame arranged to inclose said bed in the unfolded condition, means for separably engaging said bed to said frame, the latter arranged when folded to 55 form a receptacle for the folded bed, and a cap arranged to close said receptacle and hold said folded bed therein, and means for detachably securing said cap to said frame.

In testimony that we claim the invention above set forth we affix our signatures.

FRANK JOHNSON.
BURTON M. APPLEBEE.
